DESIGN FOR A DRINK MIXER

Earl S. Prince and John Brotheridge,
Rock Falls, Ill.

Application October 20, 1945, Serial No. 123,044

Term of patent 14 years

(Cl. D44—1)

To all whom it may concern:

Be it known that we, Earl S. Prince and John Brotheridge, citizens of the United States, residing at Rock Falls, in the county of Whiteside and State of Illinois, have invented a new, original, and ornamental Design for a Drink Mixer, of which the following is a specification, reference being had to the accompanying drawing, forming a part thereof.

We claim:

The ornamental design for a drink mixer, as shown.

EARL S. PRINCE,
JOHN BROTHERIDGE.
